UNITED STATES PATENT OFFICE.

FRED H. CHAPIN, OF CLEVELAND, OHIO, ASSIGNOR TO THE BOURNE-FULLER COMPANY, OF CLEVELAND, OHIO, A CORPORATION OF OHIO.

METHOD OF MOLDING SHRINK-HEAD CASINGS.

Application filed September 16, 1925. Serial No. 56,753.

To all whom it may concern:

Be it known that I, FRED H. CHAPIN, a citizen of the United States, residing in Cleveland, in the county of Cuyahoga and State of Ohio, have invented certain new and useful Improvements in Methods of Molding Shrink-Head Casings.

This invention relates to molds for making shrink head casings for ingot molds.

10 In casting steel ingots, it is customary to pour the molten metal into the mold through what is called a feeder, hot top or shrink head casing into which the molten metal rises during the latter part of the 15 pouring operation and within which a pool of molten metal is maintained long enough to feed the molten metal to the pipe or cavity naturally forming in the solidifying metal so that whatever pipe or cavity re- 20 mains in the ingot will be confined within the casing or mold top, thus largely reducing the amount of metal cropped from the ingot before it is rolled into blooms or during the blooming process.

25 Usually shrink-head casings of this kind have been made of fire clay. I have found, however, that the cost of such casings is very largely reduced by making them of blast furnace slag treated in a new way.

30 In my U. S. Patent No. 1,547,787 of July 28, 1925, I have shown and described a very efficient shrink head casing made of blast furnace slag and a binder such as cement, treated with a substance which prevents the 35 deleterious action of the gas-producing constituents of the mixture. I have found that while such casings are being molded they contract to a considerable extent and if the inner and outer walls of the mold in which 40 such a casing is formed are rigidly held until the material is fully set, hardened or solidified, internal strains are produced which cause the casing to crack or break in various places. To prevent the formation 45 of these strains or stresses and consequent cracking or breaking of the casing, I have devised a mold in which the material is molded or given shape between inner and outer walls provided with means for rigidly holding them in position until an initial 50 shape is given to the material, but which can be released from the casing at different periods during the molding operation. In practice, the inner walls are released as soon as the material has partially set, hardened

or solidified or as soon as a skin has been formed on the surface of the material sufficiently strong to support the softer material within the skin. After this, the partially solidified casing is allowed to remain 60 within the outer mold walls until it has hardened to the desired extent when the outer mold walls are released and the casing removed and given further treatment 65 when required.

While the mold constructed in accordance with my invention is especially designed to make shrink head casings of the kind shown, described and claimed in my U. S. patent above mentioned, I have found that it is 70 serviceable in molding casings made of properly treated liquid furnace slag and various other materials.

The novel features of the mold construction are claimed in my application for U. S. 75 patent, Serial No. 56,754 filed September 16, 1925. The claims herein are confined to a novel method of producing casings in accordance with my invention.

In the accompanying drawings I have 80 illustrated the best way known to me of carrying out my invention.

Figure 1 is a perspective view of a mold constructed in accordance with my invention for making shrink head casings of the general shape or form shown in my U. S. patent 85 of July 28, 1925.

Figure 2 is a top plan view of the mold illustrating how the material is molded therein and indicating how the inner walls 90 of the mold are released from the casing after the material has partially set, hardened or solidified.

Figure 3 shows a vertical central section through the mold and the casing illustrating 95 how the inner walls of the mold are held rigidly during the initial part of the molding operation.

Figure 4 illustrates how the inner walls of the mold are released from the partially 100 formed casing.

Figure 5 shows how both the inner and outer walls of the mold are released from the casing.

Both the inner and outer walls of the mold 105 are composed of a plurality of sections. In the preferred construction, the outer walls comprise two similar members A and two similar members B. The members A are of a general rectangular shape being of the 110

- same width and height. The members B are of the same size and shape and each of these members B has an inwardly projecting flange b at each end. The lower ends of the members A and B are seated in a bottom member C provided with a recess c extending continuously around the inner side of the bottom member. The lower ends of the members A and B closely fit within the recess c in such manner that they can not be moved laterally in either direction. These recesses are wide enough to accommodate not only the lower ends of the members B including the flanges b, but also the lower ends 10 of the members A. This construction is clearly shown in the drawings. In order to hold the outer walls of the mold firmly in place, I employ locking bars D which have at opposite ends arms d which 15 overlap the end portions of the members A. The distance between the two arms of each locking bar is such as to provide a space d' to receive a wedge E. When the wall members A are placed in proper position and the locking bars D are applied, the wedges may 20 be driven home in such manner as to securely lock the members A in operative position. 25 The inner walls of the mold are preferably made of eight separate pieces. There are four corner members F, all of the same size and shape and four intermediate members G, all of the same size and shape. The members G are T-shaped, each having portions g which overlap the inner ends of the corner members F and a central portion g' which is adapted to enter between the extreme inner ends of two corner members. This is indicated by dotted lines in Figure 2. 30 When the intermediate members G engage the corner pieces as shown by dotted lines in Figure 2, the inner wall of the mold as a whole is rigidly held but when the intermediate members are withdrawn in the manner indicated in Figure 2, the inner wall of the mold is released from the material being molded. 40 In order to securely lock the inner wall members in place, I employ locking blocks or bracing blocks H of the kind shown in Figure 3. Two such blocks may be used. They are somewhat longer than the distance between two intermediate members when these members are in locked position. One 45 end of each block H may be curved or rounded, as indicated at h and seated in a recess h' in one of the members G. The opposite end of the block H may abut against the opposite intermediate member G. 50 It will be understood that only two locking blocks H are necessary, one being employed between each two intermediate members G. A locking ring L is adapted to be seated in rabbets or recesses l formed in the upper 55 ends of the members F and G. The lower 60 ends of the members F and G project into a recess M in the middle portion of the bottom member C and when the ring L is applied and the blocks H are forced into active position the outer portions of the lower ends of the members F and G are pressed against the inner sides of a rib or flange N surrounding the recess M. The ring L and the flange N limit the outward movement of the members F and G when the bracing blocks 65 H are put under strain. 70 When the parts are in the condition shown in Figure 3, the material X to be molded may be poured in between the inner and outer walls of the mold and allowed to partially set, harden or solidify. In practice, it is found that a skin such as indicated at x is formed along the material if the material is allowed to stand for a few minutes, say ten to fifteen minutes. This skin is sufficiently strong to support the softer material within the skin. When the parts are 75 in the condition shown in Figure 3, the material in a liquid, plastic or semi-fluid condition is poured into the space between the inner and outer mold walls in the manner indicated in Figure 3, and the material is allowed to partially set, harden, or solidify in the manner before described. After the 80 bracing blocks H are knocked out of operative position, the inner walls of the mold collapse in the manner indicated in Figure 4. In other words, they are withdrawn from contact with the casing being formed so that the casing is allowed to freely contract as it naturally does during solidification. In this way, I prevent the presence of interior strains or stresses in the casing which would 85 occur if freedom of contraction was not provided for. 90 In the condition shown in Figure 4, the mold is allowed to stand until the material has set, hardened or solidified to the desired extent throughout the casing and then the locking bars D are removed and allowed to drop away from the casing in the manner indicated in Figure 5. The casing is now completely molded. It may in some cases be used in this condition or it may be further treated in the manner described in my patent before mentioned or in other ways. 95 The mold walls or sections are of non-resilient or rigid material as shown in the drawings and in the use of the mold the sections are rigidly connected with each other by the fastening devices shown and the mold walls can neither expand nor contract until the fastening devices are released. 100 It will thus be seen that my invention involves not only a mold of novel construction but a novel method of molding the material from which the casing is made, such method not being confined to the par-

ticular construction of mold shown in the accompanying drawings and hereinbefore described.

I claim as my invention.

- 5 1. The method herein described of making shrink head casings for ingot molds which consists in giving tubular shape to liquid or semi-plastic material while held against either expansion or contraction between rigid non-resilient inner and outer mold walls, allowing the material to partially set, harden or solidify, while so held, then releasing the material from the inner mold walls to allow the material to completely set, harden or solidify while surrounded by the rigid non-resilient outer walls of the mold, and to allow the article as a whole to contract inwardly and then separating the completed article from the outer mold walls.
- 10 2. The method herein described of making shrink head casings for ingot molds which consists in giving tubular shape to liquid or semi-plastic material while held against expansion and contraction between rigid non-resilient inner and outer mold walls, allowing the material to set, harden,
- 15
- 20
- 25

or solidify sufficiently to form a supporting skin thereon, then releasing the material from the inner mold walls to allow it to completely set, harden or solidify while surrounded by the rigid non-resilient outer walls of the mold, and to allow the article as a whole to contract inwardly and then separating the completed article from the outer mold walls.

3. The method herein described of making shrink head casings for ingot molds which consists in giving the desired form to suitable material while confined between rigidly held inner and outer walls against expansion or contraction, and then after the material has partially set, hardened or solidified, allowing the forming casing to freely contract while its inner walls are unconfined and its outer walls are closely surrounded by the rigid non-resilient outer mold walls until the article is completed, and then separating the completed article from the outer mold walls.

In testimony whereof, I have hereunto subscribed my name.

FRED H. CHAPIN.
